UNITED STATES PATENT OFFICE.

RALPH B. WILSON, OF CHICAGO, ILLINOIS.

LOOSE-LEAF-LEDGER BINDER.

No. 834,435.

Specification of Letters Patent.

Patented Oct. 30, 1906.

Application filed October 28, 1905. Serial No. 284,529.

To all whom it may concern:

Be it known that I, RALPH B. WILSON, a citizen of the United States, and a resident of the city of Chicago, county of Cook, and

5 State of Illinois, have invented certain new and useful Improvements in Loose-Leaf-Ledger Binders; and I do hereby declare that the following is a full, clear, and exact description of the same, reference being had 10 to the accompanying drawings, and to the letters of reference marked thereon, which form a part of this specification.

This invention relates to improvements in loose-leaf-ledger binders, and more particularly to an expansible ledger-binder having a closed back.

Various devices have heretofore been employed for adjusting the back-sections to afford the desired or necessary capacity for 20 devices of this class, and when adjusted the mechanism is sometimes locked to hold the parts in adjusted relation. In some instances a key is employed to operate the binder in opening and closing the same, and 25 where this is true it sometimes happens that the binder can be opened by the use of some other key somewhat resembling that of the binder or by the use of some tool or implement employed for the purpose.

30 The object of this invention is to provide a binder of the class described having an expapsible back comprising a plurality of sections operated by moving the same inwardly or outwardly to decrease or increase the capacity by means of a rotative shaft operated by a key and in which the back-sections are constructed of comparatively light material and the wearing-surfaces faced with harder material.

40 It is a further object of the invention to provide a positive lock for the shaft acting to rigidly hold the binder from unauthorized interference when in adjusted position and except by the use of a specially-prepared key.

45 The invention consists in the matters hereinafter described, and more fully pointed out and defined in the appended claims.

In the drawings, Figure 1 is an inner plan view of a binder-back embodying my invention, showing the back contracted or partly closed. Fig. 2 is a section taken on line 2 2 of Fig. 1. Fig. 3 is an enlarged section taken on line 3 3 of Fig. 1. Fig. 4 is an enlarged section taken on line 4 4 of Fig. 3. Fig. 5 is 55 an enlarged section taken on line 5 5 of Fig.

1. Fig. 6 is a section, taken on line 6 6 of Fig. 1, but showing the shaft in elevation. Fig. 7 is a side elevation of a key used in connection with my invention.

As shown in said drawings, A and A' indicate the outer or lateral back-sections, each of which are provided on the rear side or back *a* thereof with a flat contact-face of considerable width adapted to slide on a middle back-section A², which is convex on its outer 60 side and concave on the inner, affording a rounded back for the book. Integral webs a⁶ a⁷ are provided at the ends of said central back-section, closing the same. Said lateral sections A and A' are provided at their ends 65 with inwardly-directed webs a², integral with the backs and sides thereof, and inasmuch as the sections are usually formed of cast aluminum to afford a light construction steel facings a³ are rigidly secured on the inner 70 sides of said webs.

A block B is rigidly secured on the back A² adjacent the web or end wall a⁶ and is of a height sufficient to bring the same flush with the inner faces of the back *a* of the lateral 80 sections A and A'. An enlarged aperture is provided through said block and the end wall a⁶ to receive the angular end of a screw-shaft C, the opposite ends of which are provided, respectively, with right and left threads. 85 Rigidly secured upon said block B and on a corresponding block B² at the opposite end of the back-section A² are plates b and b', of steel or other suitable material, which bear against the inner hardened facings a³ on the end web 90 a² of the lateral members A A' and against the backs *a* thereof and afford a guide therefor.

Secured centrally in the back-section A² are alined bearings c, which support the unthreaded middle of the shaft, and adjacent 95 the inner ends of the threads on said shaft the shafts are turned to smaller size and straps c' are rigidly secured on the back-section A² and engage around and afford a bearing for the shaft at said points, (indicated 100 by c').

Threaded on each end of the shaft C is a nut C' and C², from which toggle-arms c¹, pivoted thereon, extend oppositely to each lateral section A A', as shown in Fig. 1, and are 105 pivotally connected at their ends therewith, so that rotation of said shaft in one direction causes said nuts to travel inwardly, increasing the capacity of the binder, while rotation of the shaft oppositely moves the nuts out- 110

wardly, thus contracting the binder. Rigidly secured upon the inner side of the back-sections A and A' are oppositely-disposed complementary telescoping impaling-posts, each comprising a section D and a section D' 5 slideable therein and which, as shown, are secured alternately on each lateral back-section and engage through suitable perforations in the rear of the sheet to be secured in 10 the binder and act to hold the same in place. The end c⁶ of the shaft projecting through the block B and end wall a⁶, as shown, is 15 rectangular in form and adapted to be engaged by a cylindric key X, having a complementary bore therein and the engaging end of which is tapered, as indicated by x in Fig. 7 and is shown in dotted lines in Fig. 4. A bolt or locking-plate E bent, as shown in Fig. 4, to afford an arm e, which engages across 20 the end of the block B, is arranged to slide along the outer face of said block between the same and the web of the lateral member A' and is notched to fit closely to the angular end c⁶ of the shaft and acts to rigidly hold the 25 same from movement. A lug e² is turned outwardly from said bolt when the notch is formed and is provided with an inclined outer end, which protrudes alongside of the shaft end beneath which the tapered end of 30 the key engages when forced inwardly and which acts to force the bolt E out of engagement with the shaft, as shown in dotted lines in Figs. 3 and 4. As shown, a strong pushing-spring E' is engaged on one of the screws e¹, 35 whereby the guide and clamping plate b' is secured on said block and is bent to press against the arm e of the bolt and acts at all times to force the bolt into positive engagement with the shaft.

40 The operation is as follows: The binder is at all times locked from interference by means of the bolt E', which positively engages and clasps the angular end of the shaft and holds the same firmly from movement, 45 and from the construction described it is evident that no key or other instrument can release said bolt other than a cylindric key tapered to engage beneath the lug e² to retract the bolt. With such a key, however, 50 the inclined or tapered end thereof is readily forced beneath the bolt, forcing the same laterally and permitting the barrel of the key to pass between the bolt and the angular end of the shaft. The shaft may be rotated in 55 either direction either to increase or to restrict the capacity of the binder, the nuts on said shaft both traveling inwardly or outwardly, dependent on the direction of rotation, and producing the characteristic adjustment of the lateral back-sections.

While I have described my invention as provided with a particular kind of impaling-posts, obviously any suitable posts for the purpose may be used and also any rotatable means 65 may be used for adjusting the binder to the

desired capacity. I therefore do not purpose limiting this application for patent otherwise than necessitated by the prior art, as obviously many details of construction and arrangement may be varied without departing 70 from the principles of my invention.

I claim as my invention—

1. In a binder of the class described the combination with rotative adjusting means of a lock therefor embracing a transversely-movable bolt adapted to engage and positively hold said adjusting means, a lug projecting outwardly from said bolt, adapted to force said bolt out of locking engagement when a key is forced on the adjusting means. 75

2. In a binder of the class described, the combination with key-operated, rotative adjusting means of a lock therefor embracing a transversely-movable bolt notched to engage and positively hold said adjusting means and integral means thereon adapted to force said bolt out of engagement when the key is forced 85 inwardly.

3. In a device of the class described the combination with a rotatable adjusting-shaft, 90 of a notched bolt extending transversely thereof and adapted to lock the same from rotation and provided with a beveled lug adapted to be engaged by a key when pressed inwardly on said adjusting-shaft. 95

4. The combination with expansible and retractable back-sections of a rotatable shaft acting to adjust the same as to capacity, an angular end on said shaft, a spring-impelled bolt movable transversely of the shaft and acting normally to positively engage the angular end thereof, and a lug on said bolt adapted when a key is forced inwardly on the shaft to retract the bolt. 100

5. In a device of the class described the combination in a loose-leaf binder having adjustable binding means, of a rotative shaft adapted to adjust the same to vary the capacity, an angular end on said shaft, a spring-impelled bolt adapted normally to rigidly engage the shaft and provided with a lug lying approximately parallel of the shaft and adapted when a cylindric key is fitted to the shaft to force the bolt out of engagement with the shaft. 110

6. In a device of the class described the combination with a central back-section of lateral back-sections carrying telescoping impaling-posts and slidably engaged on the central back-section, hardened facings provided on the wearing-surfaces of said sections, a rotatable shaft journaled on the central back-section and oppositely threaded at its ends, a complementary nut on each end, toggle-bars engaging said nuts oppositely with the lateral back-sections, an angular end on said shaft, a bolt slotted to engage said angular end and adapted when a tapered, cylindric key is applied to the shaft to move laterally out of engagement with the shaft. 125

7. In a device of the class described the combination with an adjusting-shaft having an angular end, of a block through which said angular end of the shaft extends, a bolt slideable on the face of said block and slotted to rigidly engage the angular end of the shaft, there being a lug on said bolt and having an outwardly-extending end inclined from the shaft and a spring bearing against said bolt and holding the same normally in engagement with the shaft.

8. In a device of the class described an adjusting-shaft having an angular end thereon, a transversely-slidable, spring-impelled bolt having a slotted end adapted to receive said angular end therein and hold the shaft from rotation and means extending outwardly from said bolt in close proximity with said shaft and adapted to have a key forced beneath the same to retract the bolt.

9. In a device of the class described the combination with adjustable back-sections of a rotatable adjusting-shaft therefor having an angular end, a block through which said end projects, a bolt slideable on the outer face of the block and provided with a notch adapted to engage the angular end of said shaft, a laterally-directed arm on said bolt, a spring carried on the block and adapted to engage said arm and force the bolt into engagement with the shaft and a lug carried on said bolt and extending outwardly along the shaft and provided with an inclined outer end.

In testimony whereof I have hereunto subscribed my name in the presence of two subscribing witnesses.

RALPH B. WILSON.
